(57) **CLAIM**

The ornamental design for a tool head, as shown and described.

DESCRIPTION

FIG. 1 is a right upper perspective view of a tool head showing our new design;

FIG. 2 is a right lower perspective view thereof;

FIG. 3 is a left lower perspective view thereof;

FIG. 4 is a left upper perspective view thereof;

FIG. 5 is an upper side view thereof;

FIG. 6 is a lower side view thereof;

FIG. 7 is a left side view thereof; and,

FIG. 8 is a right side view thereof.

The dash-dash broken lines illustrate portions of the tool head that form no part of the claimed design. All broken lines and unshaded surfaces bounded by broken lines form no part of the claimed design.
